[57] CLAIM

The ornamental design for an electronic apparatus, as shown and described.

DESCRIPTION

FIG. 1 is a perspective view of an electronic apparatus showing our new design;

FIG. 2 is a top view thereof on an enlarged scale;

FIGS. 3 and 4 are respectively front and rear views

thereof on an enlarged scale;

FIG. 5 is a left side view thereof on an enlarged scale;

FIG. 6 is a right side view thereof on an enlarged scale,

a portion of the housing being broken away for pur-

poses of disclosure;

FIG. 7 is a bottom view thereof on an enlarged scale;

FIG. 8 is a perspective view of a second embodiment of

our new design;

FIGS. 9 and 10 are respectively top and bottom views

thereof on an enlarged scale;

FIGS. 11 and 12 are respectively front and rear views

thereof on an enlarged scale;

FIG. 13 is a left side view thereof on an enlarged scale;

FIG. 14 is a right side view thereof on an enlarged scale,

a portion of the housing being broken away for pur-

poses of disclosure.
